CLOTH HOLDER FOR CUTTING TABLES

Joseph Herman and Jack Feuer,
Brooklyn, N. Y.

Application May 13, 1944, Serial No. 535,495

6 Claims. (Cl. 164—78)

This invention relates to cloth holders, particularly adapted for application upon cutting tables.

Broadly, it is an object of our invention to provide an easily removable pin and socket for same which can be fastened to a cutting-table in any desired position.

More particularly, it is an object of our invention to provide an inexpensive socket base and removable pin for same for use on cutting-tables which can be arranged in predetermined rows and distances for holding any desired numbers of layers of cloth stretched in position for cutting.

Heretofore, various kinds of expensive and complicated devices have been made for holding multiple layers of cloth in position upon cutting-tables. Many of these devices are cumbersome and complicated and require attention in their maintenance, such as, oiling and cleaning. In many shops the layers of goods are still fastened to the cutting-tables by the use of long nails which are hammered through the cloth into the cutting-tables, thus mutilating and damaging the cutting-table which in time must be resurfaced and eventually replaced.

We have, therefore, provided a simple and inexpensive unit in the nature of a removable pin and socket which can be so fastened to the cutting-table so that the table will not be marred nor will it be damaged by constant use.

A further object is to provide a socket for an interchangeable pin so that longer and shorter pins can be used as desired depending upon the thickness of the multiple layers to be spread. Furthermore, the pins or nails may be removed for sharpening while a reserve set is substituted without suffering the loss of use of the cutting-table or the time during the sharpening of the pins or nails.

A further object is to provide a knurled end for the pin or nail for easy gripping for removal of the pin. We have also provided, as a modification, opposed grooves and a key for same should a greater effort be necessary to remove the pin or nail from its socket.

Still a further object is to provide a base for a socket which can be used for sockets of different inside and outside diameters to accommodate nails or pins of different diameters.

Another object is to provide a socket for a removable pin which may be adjustable according to the thickness of the cutting-table.

For a fuller understanding of the nature and objects of our invention, reference is had to the

following detailed description in connection with the accompanying drawing, in which:

Fig. 1 is a fragmentary front view of a pin or nail showing the socket and base in section.

Fig. 2 is a bottom view of the base.

Fig. 3 is a fragmentary front view of a modified form of the pin of Fig. 1, showing a keyway.

Fig. 4 is a fragmentary perspective of a key to fit the keyway of the pin of Fig. 3.

Fig. 5 is a fragmentary front view of a pin and modified adjustable socket for same.

Fig. 6 is a front view of another modified socket and base for a pin.

Referring to the drawing, numeral 10 represents a base having a number of countersunk holes 11 for fastening the said base to the underneath side of a cutting table by screws 12. Base 10 has an interior threaded hole 13 in its center to receive the exterior threaded portion 14 of a socket member 15; the threaded portion 14 being smaller in diameter than the socket member, thus creating a shoulder 18. Socket member 15 has a longitudinal bore 16 and a short bore 17 at the threaded portion 14 of a lesser diameter than bore 16 thus creating a shoulder 18 for receiving the base 19 of the removable pin 20 which is adapted to fit within bore 16 of the socket member. Pin 20 is preferably made with a knurled upper portion 21 terminating in a pointed end 22. The knurled portion provides easy gripping means for the fingers in removing pin 20 while it does not interfere with the placing of fabric upon the pin 20.

Before attaching base 10 to a cutting-table 23 usually of wood and designated in dotted line, the distance from each short end of the table is determined and straight lines are drawn parallel to the short ends. A series of holes of the diameter of the socket member 15 are drilled through the table 23 spaced apart at any desired distance, but preferably equally distant. Base 10 and socket member 15 are joined together by the threaded portions 13 and 14 and the socket members are inserted through the drilled holes in the cutting-table 23 from the underneath side of the table. The socket member 15 from its shoulder 24 to its end opposite the threaded portion 14, should be of the same length as the thickness of the cutting-table 23 so as to present an even upper surface upon the cutting-table. Bases 10 are then firmly attached by screws 12 to the underneath side of the cutting-table 23 beneath each of the drilled holes in the cutting-table. A like set of pins 20 are then inserted into the longitudinal bores 16 of socket members 15. The

50

length of the pins 20 used is determined by the height of the layer of cloth to be spread upon the cutting table for cutting.

By providing the short bore 17 in the socket member 15, the longitudinal bore 16 may easily be cleaned by forcing air therethrough, or by any other desired means.

Socket members of different inside and outside diameter may be used with the same base by keeping the threaded end portion uniform; however, the transverse lines of holes drilled in the cutting table should be of the diameter of the socket members. Any desired number of transverse rows of socket members may be attached to the cutting table, since the tops of the socket members are flush with the cutting table top and do not interfere with the spreading of the layers of cloth or the cutting. Pins are inserted only in the rows of socket members used and the rows of socket members used are determined by the length of the ply or layers of cloth to be laid.

The cloth is spread in superimposed relation until the desired number of layers is spread; the cloth being engaged on the pins, as is well known in the art, preparatory for the arrangement of patterns so that the ply or stack of goods can be cut simultaneously.

In Fig. 3, the modified pin 25 is provided with a keyway 26 in the form of opposed grooves. In the event that the pin should stick within the socket member when it is attempted to be removed, a simple key 27, as shown in Fig. 4, having legs 28 adapted to fit within the grooves 26, is used to aid in the removal of the pin. Of course, any other desired type of key and keyway may be used in place of that shown in the drawing.

The socket member and base may be made of one piece, but we believe it better practice from the manufacturing standpoint to produce the unit in its preferred form, as shown in Figs. 1 and 3, since the same base can be used with different socket members.

Referring to Fig. 5, numeral 29 represents a base with countersunk holes for fastening to the underneath side of a cutting table by screws 30 as shown. Base 29 has an interior threaded hole in its center to receive the exterior threaded portion 31 of the socket member 32 which has a longitudinal bore 33 and a short interior threaded portion 34 of a smaller diameter than bore 33 thus creating a shoulder 35 for receiving the base 36 of the removable pin 37 which has a small exterior threaded extension 38 adapted to screw into the threaded portion 34 of the socket member. A longitudinal bore 40 of smaller diameter than bore 34 may be used for cleaning purposes similar to bore 17.

The socket member 32 is inserted through a bored hole in the cutting table in the same manner as socket member 15 of Fig. 1, except that it may be adjusted to the thickness of the cutting table and fixed in position by lock nut 39. We prefer to have the top of the socket member 32 a fraction below the cutting table top, as shown in Fig. 5. This type of socket member may be used on cutting table of different thicknesses and adjusted accordingly.

In Fig. 6 another modified socket and base member is shown. The socket portion 41 has an exterior spiral portion and a series of stepped internal bores, each bore of progressively smaller diameter, the central bore being threaded like that shown in Fig. 5 to receive a pin. The socket and base member is fashioned of one

piece, the base portion 42 having a wide end 43 tapering toward the socket portion, as shown. A series of lugs 44 are formed upon the tapered portion of the base.

5 In attaching the socket and base member shown in Fig. 6, a hole of a lesser diameter than the spiral portion is drilled through the cutting table and the socket and base member is driven into this hole from the underneath side of the 10 cutting table. The spiral portion makes its own thread along the interior of the drilled hole as it proceeds into the hole. When the base portion 42 is reached, the lugs 44 act as gripping members in the softer wood. The socket is driven to the 15 desired height by blows upon end 43. Of course, the length of the socket and base member used is determined by the thickness of the cutting table.

It is obvious that other changes and modifications may be made in some of the details of construction without departing from the general spirit of the invention, as set forth in the appended claims.

We claim:

25. 1. A cloth holder for cutting tables of the character described, comprising a base, screw holes in said base, a socket member having a longitudinal bore through the greatest part of said socket member and a short bore of smaller diameter than said longitudinal bore creating a shoulder 30 within said socket member, a pin longer than said socket member of the diameter of said longitudinal bore and adapted to fit within said longitudinal bore, said pin having a flat end and 35 a pointed end, said flat end adapted to rest upon said shoulder within said socket member.
2. A cloth holder for cutting tables of the character described, comprising a base, screw holes in said base, an interiorly threaded hole disposed 40 in the central portion of said base, creating a shoulder, said socket member having an exterior threaded extending portion adapted to fit within said threaded hole of said base and of greater diameter than said threaded hole, said socket 45 member having a longitudinal bore through the greatest part and a short bore of smaller diameter than said longitudinal bore creating a shoulder within said socket member, a pin longer than said socket member of the diameter of said longitudinal bore and adapted to fit within said longitudinal bore, said pin having a flat end and a 50 pointed end, a knurled portion adjacent said pointed end, said flat end adapted to rest upon said shoulder within said socket member.
3. A cloth holder for cutting tables of the character described, comprising a base, screw holes in said base, an interiorly threaded hole disposed 55 in the central portion of said base, creating a shoulder, said socket member having an exterior threaded extending portion adapted to fit within said threaded hole of said base and of greater diameter than said threaded hole, said socket member having a longitudinal bore through the greatest part and a short bore of smaller diameter than said longitudinal bore creating a shoulder within said socket member, a pin longer than said socket member of the diameter of said longitudinal bore and adapted to fit within said longitudinal bore, said pin having a flat end and a 60 pointed end, a knurled portion adjacent said pointed end, said flat end adapted to rest upon said shoulder within said socket member.
65. 4. A cloth holder for cutting tables of the character described, comprising a base, screw holes in said base, an interiorly threaded hole disposed in the central portion of said base, creating a shoulder, said socket member having an exterior threaded extending portion adapted to fit within said threaded hole of said base and of greater diameter than said threaded hole, said socket member having a longitudinal bore through the greatest part and a short bore of smaller diameter than said longitudinal bore creating a shoulder within said socket member, a pin longer than said socket member of the diameter of said longitudinal bore and adapted to fit within said longitudinal bore, said pin having a flat end and a 70 pointed end, a knurled portion adjacent said pointed end, said flat end adapted to rest upon said shoulder within said socket member, a keyway adjacent said knurled portion and a key adapted to fit within said keyway for aid in removing said pin from said socket member.

4. A cloth holder for a cutting table of the character described comprising a base, screw holes in said base, a threaded adjustable socket member having a longitudinal bore, a threaded bore of smaller diameter than said longitudinal bore and another longitudinal bore of smaller diameter than said threaded bore, a removable pin adapted to fit within said first-named longitudinal bore, said pin having a threaded extension adapted to screw into said threaded bore of said socket member.

5. A cloth holder for a cutting table of the character described comprising a base, screw holes in said base, a threaded adjustable socket member having a longitudinal bore, a threaded bore of smaller diameter than said longitudinal bore and another longitudinal bore of smaller diameter than said threaded bore, a removable

pin adapted to fit within said first-named longitudinal bore, said pin having a threaded extension adapted to screw into said threaded bore of said socket member, and a lock nut for said threaded adjustable socket member.

6. A cloth holder for cutting tables of the character described comprising a base for a removable pin, said base having an external spiral portion and a tapered end portion, said end portion having a series of lugs around the tapered portion, said base having a series of three stepped internal longitudinal bores of progressively smaller diameters, the central bore being threaded for receiving the threaded end of said removable pin.
